(57) **CLAIM**

We claim the ornamental design for a battery charger, as shown and described.

DESCRIPTION

FIG. 1 is a front perspective view of a battery charger; FIG. 2 is a back bottom perspective view of the battery charger;

FIG. 3 is a top plan view thereof;

FIG. 4 is a bottom plan view thereof;

FIG. 5 is a right elevational view thereof;

FIG. 6 is a left elevational view thereof;

FIG. 7 is a back elevational view thereof; and,

FIG. 8 is a front elevational view thereof.

The broken lines shown in the drawings of the battery charger are for the purpose of illustrating portions of the article and form no part of the claimed design.
